UNITED STATES PATENT OFFICE.

GEORGE M. EATON, OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTRIC LOCOMOTIVE.

1,080,051.

Specification of Letters Patent.

Patented Dec. 2, 1913.

Application filed June 9, 1910. Serial No. 566,108.

To all whom it may concern:

Be it known that I, GEORGE M. EATON, a citizen of the United States, and a resident of Wilkinsburg, in the county of Allegheny and State of Pennsylvania, have invented a new and useful Improvement in Electric Locomotives, of which the following is a specification.

My invention relates to electric locomotives and other railway vehicles which are propelled by relatively large electric driving motors and it has for its object to provide a locomotive that shall be relatively light in weight and at the same time capable of developing a large amount of mechanical energy for the purpose of hauling very heavy trains.

Recent experience with electric locomotives of large capacity has demonstrated the advisability of observing two fundamental principles in mounting electrical apparatus. First, the driving motors, as well as the other apparatus, should be mounted directly on the locomotive frame or other spring-borne parts of the locomotive. Second, the apparatus, including the motors, should be mounted as high as possible in order to secure a high center of gravity for the spring-borne parts and of the entire locomotive. When a locomotive, designed in accordance with the principles above set forth, is overhauled, it is necessary to lift the entire weight of the locomotive, except the wheels and axles, with the pedestal binders removed. It is usual practice, in overhauling steam locomotives, to lift the device by its extreme ends, with the pedestal binders removed, and it is advisable to so design electric locomotives that the same method of procedure may be followed without throwing excessive strains on any part of the locomotive.

According to my present invention, I provide a frame structure which is very strong vertically but is, at the same time, much lighter than frames of equal strength heretofore employed.

One feature of my invention consist in building up the side frames of steel beams or structural steel parts, such as are employed in bridge work, and so locating the side frames relative to the locomotive axles as to avoid the necessity for removing any parts, for the purpose of overhauling the locomotive, as above indicated, which mate-

rially detract from the strength of the frames.

It is well known, by those skilled in the art, that the side frames of a locomotive, as ordinarily constructed, have to be made very heavy in order to enable them to withstand the strains imposed upon them when the pedestal binders are removed and the locomotive is overhauled.

Another feature of my invention consists in so constructing the side frames as to allow the placing of such heavy pieces of equipment as transformers at a maximum height in the cab and, at the same time, to provide ample support for properly resisting strains which are attendant upon train coupling and other heavy bumping actions.

In addition to the foregoing, I provide a journal box structure which is particularly suitable for use with the structural side frame which I prefer to utilize.

Figure 1 of the accompanying drawings is a partially sectional elevation of an electric locomotive constructed in accordance with my invention. Fig. 2 is a plan view of the running gear and lower side frames of the locomotive. Figs. 3 and 4 are detail views of the side frames shown in Figs. 1 and 2, and Figs. 5 and 6 are, respectively, a sectional elevation and a front view, with certain of the parts broken away, of a bearing box embodying my invention. Fig. 7 is a detail view of a portion of one of the members shown in Figs. 5 and 6.

Referring to Figs. 1, 2, 3 and 4 of the drawings, the locomotive here shown comprises a plurality of main driving wheel axles, 1, 2, and 3, bogie trucks 4 (only one of which is shown) side frames 5, a cab or body 6 and electric driving motors 7, 8, 9 and 10. Each of the bogie trucks 4 comprises an auxiliary driving axle 11 and a guide wheel axle 12 and is connected to the locomotive frame by means of a center pin 13 about which it is adapted to swivel, in the usual manner. In order to reduce the wear on the leading wheels of the bogie truck, which is due to the grinding action between the wheel flanges and the rails when the locomotive is rounding curves, it may be found preferable to control the bogie trucks by means of a radius bar, so arranged that the lateral center lines of the truck parallel to the axles and half way between them shall be radial relative to the curve centers, the trucks be-

ing loaded by friction plates like the leading half of a Mallet locomotive. The locomotive frame 5 comprises lower side frames 14 and 15 which are outside the driving 5 wheels 16 of the locomotive and are supported, by springs and equalizers, upon journal boxes 17, in the usual manner, truss beams 18 and 19 and a plurality of cross ties 20 and 21. The cross ties 20 support the center pins 13 and are relatively strong in 10 order to render the frame particularly rigid at its ends, which terminate in projections 22, as shown in Fig. 2. The cross ties 21 are located between the driving axles of the locomotive and support the motors 7, 8 and 15 9. The truss beams 18 and 19 form a part of the side frames, at their ends, and each of them is provided with an elevated beam 23 which is connected to one of the lower side 20 frames by means of uprights 24 and is connected by means of oblique beams or rods 25. The structure is such as to provide a maximum carrying strength with a minimum weight, 25 the uprights 24 being joined to the lower side frames between the drivers and at the ends of the cross ties 21.

The detailed structure which I prefer to employ is clearly shown in Fig. 4 of the 30 drawings, to which reference may now be had. Each of the lower side frames is composed of four longitudinal channel beams 26, 27, 28 and 29, of which the channel beam 29, constituting the lower inside edge of the 35 frame adjacent to the drivers, is removable. The channel beams 26 and 27 are secured to a projection 30 of each of the cross ties 21 and are relatively close together, while the channel beam 28 is secured to a projection 31 which extends downwardly from the 40 cross ties 21 and is offset relative to the projection 30. The arrangement of parts is such that the channel beam 29 lies in substantially the same vertical plane as the 45 channel beam 27, while the channel beam 28 is more remote from the central plane of the locomotive than the channel beam 26 in order to permit of the removal of the driving wheel axles, as hereinafter pointed out.

50 While, as illustrated in the drawings, the side frames may comprise a detachable section 29, the point which I desire to emphasize is that it also comprises a continuous beam 28 or some similar part which is materially below the center of the axles and is so placed that the wheels and axles may be removed without disturbing this element of the side frame, thereby enormously increasing its strength without adding materially to its weight.

55 Each of the bearing boxes 17 comprises a box 32, a semi-cylindrical bearing member or brass 33 and an oil cellar 34. The box is held in position by the legs 35 and 36 of a 60 U shaped pedestal 36^a which is located be-

tween and is secured to the channel beams 26, 27, 28 and 29. Spacing shoes 37, which are of U shape in horizontal section, are introduced between the box and the pedestal legs 35 and 36, a proper relation being 70 maintained between these members by means of a wedge 38 which is disposed and is adjusted in the usual manner by means of an adjusting screw 39. The member 33 is held in the box and rests on the axle in the usual manner. The inner corners of the oil cellar 34 are notched, as shown in Fig. 7, to register with projections 34^a which extend inwardly from the side walls of the box. The cellar is provided with projections 40 which, when the cellar is in position, are adjacent to projections 41 of the box, a pin 42 being thrust through holes in the two sets of projections to hold the cellar in place.

80 The bogie truck 4 may be of any suitable structure but I prefer to employ larger wheels at the inner end of the truck and to associate an electric driving motor therewith, in order that these wheels may assist in propelling the locomotive. The wheel axle 11 of the bogie truck is entirely inside of the locomotive frame, but the formation of the frame is such that the wheels of the wheel axle 12 are outside the frame, being adjacent to the projection 22. The structure of the bogie truck is immaterial to my invention and the locomotive weight which is borne by it is taken by suitable friction plate links, or in some well known manner, depending on the truck employed, and is distributed through the truck frame 43, by the usual springs (not shown) and equalizers, to the truck bearings and to the wheel axles 11 and 12.

90 Assuming that the locomotive is assembled as shown in the drawings and that it is desired to remove the driving wheel axles, the channel beams 29 will first be detached, the pins 42 will then be withdrawn from the bearing boxes and the oil cellar removed. There is now nothing to prevent the locomotive from being lifted from the axles.

100 It is evident that the structure of the side frames may easily be modified so that it is unnecessary to remove any of the parts in order to separate the frame from the axles and that the channel beam 29 may be divided into sections, if desired, within the spirit and scope of my invention. Other structural modifications may, of course, be effected, and I desire that the scope of my invention shall only be limited by the appended claims.

110 I claim as my invention:

120 1. A railway vehicle comprising a plurality of wheel axles and a pair of trussed side frames comprising beams that extend longitudinally of the locomotive and below the axles and are located outside the vertical 130

planes of the axle ends to permit vertical removal of the axles.

2. A railway vehicle comprising a plurality of wheel axles and a pair of trussed side frames comprising beams above the axles and beams below the same, all of said beams extending longitudinally of the locomotive and the outermost lower beams being located outside the vertical planes of the 10 axle ends to permit vertical removal of said axles.

3. A railway vehicle comprising a plurality of wheel axles and trussed side frames each of which has a beam above the plane of 15 the axles and a pair of beams materially below the same, the inside lower beam being detachable to permit removal of the wheel axles.

4. A railway vehicle comprising a plurality of wheel axles and structural side frames supported on the axles, each side frame having two beams below the plane of the axles, one of which is detachable to permit removal of all of the wheel axles, as 25 desired.

5. A railway vehicle comprising lower side frames having bearing boxes adjustable therein in vertical planes, a plurality of cross ties disposed between the bearing boxes, and truss beams secured to the lower side frames 30 at their ends and supported therefrom at the intermediate cross ties by means of uprights.

6. A railway vehicle comprising lower side frames having bearing boxes adjustable therein in vertical planes, a plurality of 35 cross ties disposed between the bearing boxes, and truss beams secured to the lower side frames at their ends and supported therefrom at the intermediate cross ties by means of uprights, a single section of each 40 lower side frame being detachable to permit removal of the wheel axles, as desired.

In testimony whereof, I have hereunto subscribed my name this 31st day of May, 1910.

GEORGE M. EATON.
